VICTOR H. CAROUSO, OF OAKLAND, CALIFORNIA, ASSIGNOR TO DUART MANUFACTURING CO. LTD., OF SAN FRANCISCO, CALIFORNIA, A CORPORATION OF CALIFORNIA

PERMANENT HAIR WAVER

Application filed February 11, 1929. Serial No. 339,204.

The invention relates to improvements in a permanent hair waver, a device for imparting to the human hair what is commonly known as a permanent wave which result is obtained by dampening the hair in a solution then winding wisps of the hair on a mandrel and drying the hair in the presence of heat.

An object of the invention is to produce a device of the character described having means for reducing the temperature of the outer walls thereof in order to avoid the accidental burning of a person while manipulating the heater which it is necessary to maintain at a more or less high temperature in order to obtain satisfactory results, while at the same time maintaining a sufficient degree of heat within the heating tube to effectively dry the hair therein and thereby impart to it a fixed wave or curl.

A further object of the invention is to produce a device of the character referred to which may be struck from sheet metal, thus making the production thereof in quantities economical of manufacture.

Further objects and advantages of the invention will appear from the following detailed description taken together with the drawings which form a part of the specification and in which:

Figure 1 is a side elevation of one of the cooperating tong like members showing the fins on the cross-section thereof.

Figure 2 is a perspective of one of the operating tong like members showing the inner face of the cross-section thereof.

Figure 3 is a vertical section of the assembled members taken on line 3-3 of Figure 1 showing the levers and their associate elements in full lines.

For a more complete and comprehensive understanding of the device reference may now be had to the drawings in which like reference characters indicate like parts throughout the several figures.

Reference characters 10 and 11 indicate the levers which are pivotally related to each other by a substantially V-shaped leaf spring 12 which may be secured to the levers in any suitable manner as by rivets 13, the levers 10

and 11 being urged outwardly at their upper ends and inwardly at their lower ends by the action of the leaf spring 12. Levers 10 and 11 which are substantially identical in construction are so formed by their lower portions 16 as to be of semi-elliptical shape in cross-section, thereby forming the outer walls of a substantially elliptical shaped tube in cross-section when assembled, which tube is open at both ends as clearly shown in Figure 3. Secured to the outer face of the bent lower portions of levers 10 and 11 are recessed shells 14, which recesses are open at their respective ends, thereby forming an air passage between the shell and the outer wall of the tube for cooling the outer surface thereof. Shells 14 are provided with fins 15 which act as heat radiators and are naturally cooler at their apexes by reason of their vertical thickness than the shell is at the base of the rib, thereby further guarding against accidental burning by a person handling the heater. Intermediate the outer walls 16 and the inner walls 18 of the heating element casings of the tube are electric heating elements 17 which extend outwardly of the tube and are incased in insulating blocks 22 having sockets therein for receiving plugs 19 of electric wires 20 which lead to a source of electric current. Suitable insulation is provided intermediate the electric heating element and the walls 16 and 18 of the heating tube. Wire 21 is for the purpose of connecting the heating elements 17 in the electric circuit.

After the hairs of a person's head have been dampened with a suitable solution they are gathered into wisps and wound around a mandrel and a layer of suitable fabric placed over the wound hair, when the levers 10 and 11 may be grasped at their upper ends and forced inwardly thus forcing apart the semi-elliptical tube portions for the reception therebetween of the mandrel with the hair wound therearound, when the pressure on the upper portion of the levers 10 and 11 may be released and the semi-elliptical portion forced together under the action of the leaf spring 12, thus enclosing the hair within the heating tube and the electric current passed through the heating elements.

Having thus described my invention, what I claim is:

1. A permanent hair waver comprising two semi-elliptical hingedly related members, heating elements within the members and air chambers open at their respective ends intermediate the heating element and the outer surfaces of the semi-elliptical members. 5
10. 2. A permanent hair waver comprising two semi-elliptical hingedly related members, having heating elements, and air passages open at their respective ends formed within the members and intermediate the elements and the outside surface of the semi-elliptical members. 15
15. 3. A permanent hair waver comprising two semi-elliptical members hingedly related to each other by means of a leaf spring, heating elements within the semi-elliptical members each of said members having an air passage open at its respective ends intermediate the heating elements and the outer surfaces of the semi-elliptical members. 20
20. 4. A permanent hairwaver comprising a pair of cooperating levers, a leaf spring interposed between the levers, semi-elliptical clamping members carried by the lower ends of the levers, shells having air passages therethrough affixed to the outer faces of the lower portions of the levers, heating units intermediate the lower portions of the levers and the inner portions of the shells and fins extending from the outer surfaces of the shells. 25
25. 5. A permanent hair waver comprising coacting arcuately formed pressure members, a heating element in each of said pressure members, an elongated aperture passing longitudinally through said pressure members outwardly of said heating elements, a pair of spring related handles fixed to said pressure members and a flexible electric connection for said heating elements. 30
30. 6. A permanent hair waver comprising a pair of heating elements enclosed in adjacent faces of coacting clamping members having concave adjacent faces and convex, finned outer surface, an elongated aperture passing longitudinally through said clamping members intermediate the root of the fins and the heating element, handles integral with said clamping members and extending outwardly in transverse cooperating relation, and a substantially U shaped leaf spring fixed between said handles adapted to hingedly connect said handles and coincidentally react to close said clamping members. 35
35. 7. A permanent hair waver comprising coacting concave face clamping members, handles affixed thereto and transversely related to the axis thereof, said handles having fixed to their adjacent faces the opposite legs of a U shaped leaf spring, with inwardly disposed bend, heating elements within and adjacent the faces of said clamping members, said clamping members having an elongated aperture passing longitudinally therethrough outwardly of said heating element, and a plurality of radiating fins formed on the outer surface of said clamping members, and means for connecting said heating elements in circuit with a source of electric power. 40
40. 8. A permanent hair waver having cooperating resiliently closed heating members, said heating members each comprising a housing having arcuately formed inner and outer surface, the outer surface having a plurality of transverse heat radiating ribs, an arcuately formed elongated aperture extending longitudinally through said housing and arcuately formed insulated heating elements removably attached to the inner surface of said housing, handles affixed to said housings transversely to the axis thereof and hingedly related by means of a return bend leaf spring, and electrical connections to said heating elements. 45
45. 9. A permanent hair waver, comprising a pair of coacting clamping members with adjacently disposed insulated heating elements removably attached thereto and provided with flexible connection means for an electric circuit, a backing for each of said heating elements having a concave inner face, a convex outer surface with a plurality of heat radiating ribs, an elongated ventilating aperture extending longitudinally through the body portion of said backing, means for attaching said heating element to said backing, handles fixed to said backing and extending outwardly and transversely to the axis thereof, and a U shaped leaf spring cooperating with and fixed to said handles. 50
50. 10. A permanent hair waver comprising in combination with a pair of insulated electric resistance heating units and a source of electric current, a pair of handles affixed to a pair of coacting heating unit supports, said supports having means for removably attaching said heating units to the inner surface thereof, a plurality of heat radiating ribs on the back thereof and ventilating apertures passing longitudinally through the body portion of said supports, and a U shaped leaf spring fixed to and between said handles. 55
55. 11. In a hair waving device, a structure comprising a pair of metallic members adapted to engage opposite sides of a mass of coiled hair, and electrical means for heating at least one of said members, and an insulating structure adapted to normally cover the outer surfaces of said first structure, said insulating structure being arranged to provide heat insulating air spaces between said structures. 60
60. 12. In a hair waving device, a structure comprising a pair of metallic members 120
65. 125
70. 130

adapted to engage opposite sides of a mass of coiled hair and electrical heating means for heating at least one of said members, a structure of insulating material adapted to normally cover the outer surfaces of said first structure and being arranged to provide insulating air pockets between said structures, and a handle portion of insulating material for the device.

10 13. In a hair waving device, a structure comprising a metallic member having a curved inner surface adapted to engage a side of a mass of coiled hair, electrical means for heating said member, and a heat insulating structure adapted to normally cover the outer surface of said first structure, said heat insulating structure being arranged to provide a heat insulating air space between said structures.

20 In testimony whereof I have affixed my signature.
